Inventor:

Emil Koll.

UNITED STATES PATENT OFFICE.

EMIL KOLL, OF CINCINNATI, OHIO.

PIANO-FLANGE.

1,353,596.

Specification of Letters Patent. Patented Sept. 21, 1920.

Application filed February 13, 1919. Serial No. 276,705.

To all whom it may concern:

Be it known that I, EMIL KOLL, a citizen of the United States, residing in Cincinnati, in the county of Hamilton and State of Ohio, have invented new and useful Improvements in Piano-Flanges, of which the following is a specification.

An object of my invention is to produce a piano hammer which is more easily dismantled and removed from the flange rail than piano hammers heretofore constructed and known to me.

A further object is to produce a piano hammer in which improved means are provided for adjusting and eliminating excessive wear.

These and other objects are attained in the piano hammer described in the following specification and illustrated in the accompanying drawing in which:—

Figure 1 is a side elevation of a piano hammer embodying my invention.

Fig. 2 is a front view of my improved piano hammer.

Fig. 3 is a front view of the hammer mounting flange embodying a feature of my invention.

Fig. 4 is a side view of the flange shown in Fig. 3.

Fig. 5 is a rear view of the flange shown in Figs. 3 and 4.

My invention relates particularly to the mounting means of piano hammers, and consists of a hammer flange 6 which is secured to the flange rail 7 by a screw 8, and a flange clip 9 which secures the hammer butt 10 to the flange by means of its clamping action upon the center pin 11.

At its lower end the flange 6 is forked to permit the screw 8 to occupy the space between the branches thereof and thus afford adjustment of the hammer. Above the

fork a groove 12 is formed, in which the end 13 of the flange clip is located, and at the upper end of the flange and flange clip 45 are grooves 14 and 15 which permit of the clamping therein of the center pin 11 when screw 8 is tightened.

In assembling my improved construction the flange is located to the rear, with the 50 flange clip in front. This brings the screw 16 in front and in accessible position without having to remove the flange in order to get at the screw 16, as is customary in flange construction now in use.

Another feature of my invention is that the groove 12 coöperates with the inturned end 13 of the clip to preserve perfect alignment of the upper end of the flange and the clip so that there can be no binding of the 60 upper ends of the flange and clip between the sides 17 and 18 of the hammer butt 10.

Having thus described my invention what I claim is:—

A piano flange having parallel front and 65 back surfaces and a slot therein adapting the flange to be adjustably secured to a piano flange rail, said flange having a groove 70 therein, a flange clip having an inturned end adapted to occupy the groove, a screw entering the flange rail from the front and occupying the slot, and a second screw passing through the flange clip from the front and entering the flange, said flange and clip having 75 registering grooves on their contacting surfaces to receive the center pin of the butt.

In witness whereof I affix my signature in the presence of two witnesses.

EMIL KOLL.

Witnesses:

B. THOMAS ELLIS,
WILLIAM JOHN SCHULTZ.
